UNITED STATES PATENT OFFICE.

ERASTUS T. JONES, OF WAYLAND, TEXAS, ASSIGNOR OF ONE-HALF TO CHARLES H. STANTON, OF WACO, TEXAS.

CHURN-ACTUATING MECHANISM.

1,156,146.

Specification of Letters Patent.

Patented Oct. 12, 1915.

Application filed October 9, 1914. Serial No. 865,893.

To all whom it may concern:

Be it known that I, ERASTUS T. JONES, a citizen of the United States, residing at Wayland, in the county of Stephens and State of Texas, have invented a new and useful Churn-Actuating Mechanism, of which the following is a specification.

The present invention appertains to churn actuating mechanisms, and aims to provide a novel and improved appliance for enabling a churn to be operated by means of a rocking chair.

The present invention contemplates the provision of a churn actuating mechanism having unique means for the application of an ordinary or rocking chair thereto in order that the oscillatory movement of the chair will impart movement to the mechanism, the mechanism also embodying novel means for operatively connecting the chair with the churn dasher.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawing, wherein:

Figure 1 is a plan view of the improved mechanism. Figs. 2 and 3 are vertical sections taken on the lines 2-2 and 3-3 respectively of Fig. 1.

In carrying out the present invention, there is provided a frame or base 1 including the parallel side beams or sills 2, and a teeter or rocking platform 3 is mounted between the beams or sills 2, bars 4 being preferably secured to the side edges of the platform 3 and engaging the rock shaft 5 which is journaled through the beams or sills 2. The platform or teeter 3 is thus mounted for rocking or oscillatory movements upon the base 1.

In order to attach a chair upon the platform or teeter 3, a cleat 6 is secured upon the platform 3 adjacent its rear end and transversely of the platform, and a transverse adjustable cleat 7 is mounted upon the

platform 3 adjacent its forward end, and carries a clamping bolt 8 intermediate its ends which is engaged through a longitudinal slot 9 provided in the platform 3. Thus, when the bolt 8 is loosened, the forward cleat 7 may be adjusted longitudinally of the platform.

As illustrated in the drawing, a rocking chair 10 is applied to the platform or teeter 3, the rockers 10^a resting upon the central portion of the platform 3 and having their rear portions resting upon the rear cleat 6. A forward cleat 7 is adjusted rearwardly so as to wedge between the forward end portions of the rockers 10^a and the platform 3, to hold the rocking chair 10 steady upon the platform 3, and straps or other retaining elements 11 are engaged through the platform 3 and around the rockers 10^a between the cleats 6 and 7 to hold the chair 10 down upon the platform. In this manner, the chair 10 is attached rigidly to the platform in order that when the chair is rocked, the platform will be oscillated therewith.

An ordinary chair may also be applied to the platform 3, the rear legs thereof being adapted to rest upon the platform and against the cleat 6, while the cleat 7 may be slid rearwardly against the forward legs of the chair. The straps 11 may then be passed around the lower side rungs of the chair to hold the chair in place, and whereby the platform 3 will oscillate with the chair. Various chairs may be applied to the platform or teeter.

In order to assist the operator in rocking the chair, inclined supports 12 are secured to the forward ends of the beams or sills 2, and carry a foot piece 13. The base or frame 1 is provided at one side of the platform or teeter 3 with an upstanding portion or standard 14 attached to the corresponding beam or sill 2, and a lever 15 is fulcrumed to the standard 14 above the platform 3. A lever 16 is attached to that end of the rock shaft 5 below the lever 15, and links 17 connect the corresponding arms of the levers 15 and 16; whereby the lever 15 will be oscillated with the platform 3. The lever 15 is provided with an upper segment 18 intermeshing with a pinion 19 secured upon a shaft 20 journaled through the standard 14 above the lever 15. A relatively large bevel gear 21 is secured upon the shaft 20 and intermeshes with a relatively small bevel 110

pinion 22 keyed upon an upright counter shaft 23 journaled through the upper portion of the standard 14. A relatively large spur gear 24 is keyed upon the upper end of 5 the counter shaft 23 and intermeshes with a relatively small pinion 25 keyed upon the upper end of the dasher staff or shaft 26 which is journaled through the upper portion of the standard 14. The dasher staff 10 26 is preferably adjustable and passes into the churn body 27, which may be of any suitable character, and a dasher or agitator 28 may be carried by the staff 26 within the churn body for churning or agitating the 15 contents thereof. The agitator 28 embodies the lower perforated plate 28' attached to the lower end of the staff 26, and an arched spider 28^a having the ends of its arms secured to the perforated plate 28' and having 20 its central or hub portion secured to the staff 26. The spider 28^a will agitate the contents of the churn from the top to the bottom thereof, and the perforated plate 28' will enable the butter or solidified matter 25 to be readily lifted out of the churn. A hood or guard 29 is adjustably carried by the dasher staff 26 above the churn body 27 to protect the same.

In operation, after the chair has been 30 properly applied to the platform or teeter, and the churn body 27 properly assembled with the mechanism, the operator being seated upon the chair may readily rock the same in the usual manner. It is preferable 35 for the operator to place his or her feet upon the foot piece 13, to facilitate the oscillation of the chair. As the chair is rocked, the platform 3 is rocked therewith, and as a result the lever 15 will be swung 40 back and forth. During each oscillation of the lever 15, the gear train 18, 19, 21, 22, 24 and 25 will cause the dasher staff to rotate a number of times, so that the dasher staff will be alternately rotated in opposite directions 45 during the rocking of the chair and platform. In this manner, the contents of the churn may be readily churned or agitated without any inconvenience and hardship upon the operator.

50 It is preferable to connect the forward

portion of the platform 3 and the base frame by a contractile spring 30, which will return the rocking chair and platform to forward position, after the chair has been thrust rearwardly by the operator. This 55 will enable the device to be conveniently operated.

Having thus described the invention, what is claimed as new is:—

1. In a device of the character described, 60 a base, an oscillatory platform mounted thereon, a pair of cleats mounted on the platform to engage the rockers of a rocking chair, one of the cleats being adjustable, means carried by the platform between the 65 cleats for securing the rockers upon the platform between the cleats, a dasher, and means operatively connecting the dasher and platform for operating the dasher when the platform is oscillated. 70

2. In a device of the character described, 75 a base, an oscillatory platform mounted thereon, the base having a standard at one side of the platform, a rotary dasher staff carried by the standard, a lever fulcruated to the standard and having an upper segment, a link connecting the lever and platform, and a train of gears carried by the standard for rotating the dasher staff and including a gear engaging said segment. 80

3. In a device of the character described, 85 a base, a platform mounted for oscillatory movement upon the base, a chair secured upon the platform, a foot rest carried by the forward end of the base, a standard attached to the base at the side of the said platform, a dasher stamp carried by the standard, means carried by the standard and operatively connecting the dasher staff and platform, and a spring between the platform 90 and base whereby the spring tends to swing the chair toward the foot rest.

In testimony that I claim the foregoing as my own, I have hereto affixed my signature in the presence of two witnesses.

ERASTUS T. JONES.
